DESIGN FOR A FLUORESCENT LAMP FIXTURE

Pasquale J. Lepore, Somerville, Mass.

Application June 14, 1944, Serial No. 113,997

Term of patent 14 years

(Cl. D48—23)

To all whom it may concern:

Be it known that I, Pasquale J. Lepore, a citizen of the United States, residing at Somerville, in the county of Middlesex and State of Massachusetts, have invented a new, original, and ornamental Design for a Fluorescent Lamp Fixture, of which the following is a specification, reference being had to the accompanying drawing, forming part thereof.

Figure 1 is a front perspective view of a fluorescent lamp fixture showing my new design; and Figure 2 is an end view of the same.

The rear of the fixture is a substantial duplicate of the front shown in Figure 1.

I claim:

The ornamental design for a fluorescent lamp fixture, as shown and described.

PASQUALE J. LEPORE.
